DESIGN FOR A COMBINED WASTE RECEPTACLE AND ILLUMINATED TOP THEREFOR

Lester E. Stewart, Albany, N. Y.

Application October 10, 1933. Serial No. 49,448

Term of patent 7 years

To all whom it may concern:

Be it known that I, LESTER E. STEWART, a citizen of the United States, residing at Albany, in the county of Albany and State of New York, have invented a new, original, and ornamental Design for a Combined Waste Receptacle and Illuminated Top Therefor, of which the following is a specification, reference being had to the accompanying drawing, forming part thereof.

Figure 1 is a perspective view of a combined waste receptacle and illuminated top therefor, showing my new design.

Figure 2 is a view in front elevation.

I claim:—

The ornamental design for a combined waste receptacle and illuminated top therefor, as shown.

LESTER E. STEWART.
